CLAIM

The ornamental design for a hot air brush as shown and described.

DESCRIPTION

FIG. 1 is a perspective view of a hot air brush showing my new design;

FIG. 2 is a front view thereof;

FIG. 3 is a rear view thereof;

FIG. 4 is a left side view thereof;

FIG. 5 is a right side view thereof;

FIG. 6 is an enlarged top view thereof;

FIG. 7 is an enlarged bottom view thereof; and

FIG. 8 is an enlarged view of portion “8” shown in FIG. 1; and,

FIG. 9 is an enlarged view of portion “9” shown in FIG. 1. The dash-dash broken lines shown in the drawings depict portions of the hot air brush, and form no part of the claimed design. The dot-dash broken lines seen in FIGS. 1 and 8-9 are for the purpose of depicting enlarged view indicators, and form no part of the claimed design.

1 Claim, 9 Drawing Sheets
